DESIGN.

—o—
W. L. JACOBS.

CARPET.

No. 17,253.

Patented Apr. 12, 1887.

UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 17,253, dated April 12, 1887.

Application filed February 23, 1887. Serial No. 228,621. Term of patent 34 years.

To all whom it may concern:

Be it known that I, WINTHROP L. JACOBS, of East Orange, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

The main feature of the design consists in the closely-grouped irregularly-shaped coral-like figures, as shown in the photograph. The more important ones of them are respectively

marked A, B, C, D, E, F, G, H, and J in the photograph. They are all of nearly the same general mass size, but differ in shape and in the character of coral-like ornamentation and outline and coral-like connected projecting parts. The figures are all clearly shown in detail in the photograph.

What I claim as new, and desire to secure by Letters Patent, is—

The design for carpets, consisting of the coral-like figures A, B, C, D, E, F, G, H, and J, and the other coral-like figures, substantially as shown and described.

WINTHROP L. JACOBS.
